UNITED STATES PATENT OFFICE.

JOSEPH L. O'BRIEN, OF SOUTH NORWALK, CONNECTICUT.

ELECTRIC HAT-CURLING IRON.

No. 874,029.

Specification of Letters Patent.

Patented Dec. 17, 1907.

Application filed July 1, 1907. Serial No. 381,715.

To all whom it may concern:

Be it known that I, JOSEPH L. O'BRIEN, a citizen of the United States, residing at South Norwalk, county of Fairfield, State of Connecticut, have invented a new and useful Electric Hat-Curling Iron, of which the following is a specification.

This invention relates more especially to the art of hatting, and has for its object to provide a simple, light and relatively inexpensive shackle or iron for performing the operation of curling, which will avoid the objections to the various heavy and cumbersome tools heretofore used for this purpose and which will perform the operation of curling in an easier, quicker and more effective manner than has been possible with any curling iron heretofore produced.

It is, of course, well understood that in curling the brims of both soft and stiff hats the brims are softened by moistening them and are then shaped to a given design by shrinking the edge of the brim by means of heat and pressure. Heretofore, so far as I am aware the curling irons used in this art have been heated either by means of gas stoves or by means of heated slugs placed therein which has necessitated that the irons be made cumbersome and heavy. In use, as soon as the iron was placed in contact with a hat brim saturated with cold water, the heat of the iron was quickly lost by absorption and the efficiency of the iron greatly diminished, necessitating the application of another tool to complete the process, this second tool being a cumbrous shell weighing ten or twelve pounds.

My present invention enables me to provide a simple and easily handled iron which is highly heated and remains heated at just the point at which most heat is required, and which enables the operator to complete the operation of curling without the use of a secondary tool.

With this and other objects in view the invention consists in certain constructions and in certain parts, improvements and combinations which will be hereinafter described and then specifically pointed out in the claims hereunto appended.

In the accompanying drawing forming a part of this specification, Figure 1 is an elevation of my novel curling iron as in use; Fig. 2 a section on the line 2—2 in Fig. 1 looking in the direction of the arrows; Fig. 3 a plan view of the iron, the arms of the han-

dle being in section on the line 3—3 in Fig. 1; and Fig. 4 is an inverted plan view of the intermediate section.

10 denotes the lower or working section, which is an elongated casting, one edge of which is a concave curve as at 11 and which is provided just back of the concave lower edge with a curved groove 12. This groove receives the edge of the hat brim to be operated upon, the edge of the brim being curved over a form, indicated by 13, lying in the groove, as clearly shown in Fig. 2. The form is provided with attaching plates indicated by 14 having slots 15 and is adjustably secured in place by means of screws 16 passing through the slots and engaging an intermediate section indicated by 17. The lower section is provided with upwardly extending rods 18 which are threaded at their upper ends. In the present instance, in addition to the lower and intermediate sections, I have shown the iron as comprising an upper section indicated by 19, this upper section, however, not being an essential feature of construction. Rods 18 pass through holes in sections 17 and 19 and through the handle which is indicated as a whole by 20, the parts of the iron being secured together by nuts 21 engaging the threaded upper ends of the rods and bearing upon the base of the handle, washers 22 being shown as interposed between the nuts and the handle. The handle comprises a base indicated specifically by 23, arms extending therefrom and indicated by 24 and a hand piece of wood or other insulating material indicated by 25 which is secured to the arms. In order to keep the upper section and the handle as cool as possible, I place a heat insulating layer of asbestos or other suitable material, indicated by 26, between the intermediate and the upper sections. In order to increase the amount of radiating surface and thereby reduce the temperature of the upper section and make the iron pleasant to handle, I provide the top of the upper section with transverse grooves indicated by 27.

The gist of the invention lies in the means for heating the lower and intermediate sections. 28 denotes the current wires which are connected to binding posts 29. These binding posts pass through an extension of the intermediate section, which is indicated by 30, are insulated therefrom as at 33 and are covered by a cap 31 which is secured to the extension by a screw 32. The interme-

diate section acts as a heat reservoir. The heating of the lower and intermediate sections is effected by means of a continuous laminated resistance member slotted alternately from opposite edges superposed in flattened coils and embedded in sheets of mica or other suitable electrical insulating and heat conducting material. The resistance member as a whole is indicated by 34, 5 the slots by 35 and the sheet mica or other electrical insulating heat conducting material by 36. The resistance member may be made from nickel steel, German silver or any suitable resistance material, and of any 10 required length, and the ends of said strip are connected to the respective binding posts. In the drawing (see Fig. 4), I have illustrated a form of resistance member consisting of four laminæ. Suppose, by way of 15 illustration, that the current passes from one of the binding posts to the lamina indicated specifically by *a*. This lamina passes substantially the length of the sections and is bent upon itself and lamina *b* extends in the 20 opposite direction nearly to the other end of the sections, where it is bent upon itself, extends transversely across the sections and lamina *c* extends to the opposite end again and is then bent upon itself, and lamina *d* 25 extends to the other binding post, the several laminae being continuous. Laminae *a* and *d* are separated from section 17, and laminae *b* and *c* are separated from section 10 by means 30 of mica or other suitable electrical insulating heat conducting material and similar electrical insulating heat conducting material is interposed between laminae *a* and *b* and between laminae *c* and *d*.

By using a resistance member consisting 40 of superposed laminae or flattened coils, and embedding said laminae or flattened coils in sheet mica, or its equivalent, I am enabled to secure any required degree of heat in a minimum amount of space and to provide a very 45 small, light and easily handled tool that will perform its work in a much quicker and more effective manner than any tool of the character heretofore produced. In order to provide the greatest amount of heat continuously at the point where most heat is required, I curve lamina *c* outward to or approximately to the edge of the iron at the center of groove 12, as is clearly shown in Fig. 4.

50 By so constructing the iron that heat is continuously imparted to the lower section directly above the groove, the water in a hat brim being operated upon is converted into steam and the brim is shrunk to form in an easier, quicker and more satisfactory manner than has heretofore been possible.

It will, of course, be understood that the invention is not limited to the special details of construction illustrated in the drawing, 55 but that these details may be greatly varied

without departing from the principle of the invention.

I claim:

1. In a tool of the character described, the combination with a working section, of means for heating said section consisting of a laminated resistance member disposed adjacent to said working section, said resistance member extending longitudinally of the working section and being bent upon itself and extending backward, then bent upon itself and extending transversely, then bent upon itself and extending longitudinally and then bent upon itself and extending backward and insulating material between the laminae of the resistance member and between the resistance member and other portions of the iron.

2. In a tool of the character described, the combination with a working section provided with a concave groove to receive a hat brim, of means for heating said section consisting of a laminated resistance member slotted alternately from opposite edges and extending longitudinally of the section in superposed laminae, then transversely and then longitudinally again in superposed laminae, one of said laminae being curved outward toward the center of the groove, substantially as described, for the purpose specified.

3. A flattened resistance member consisting of continuous laminae of metal slotted alternately from opposite sides, said member extending longitudinally being then bent upon itself and extending longitudinally again, then transversely, then longitudinally and then longitudinally again.

4. In a tool of the character described, the combination with a lower section having a concave groove to receive a hat brim, an intermediate section and a form for a hat brim lying in the groove and secured to the intermediate section, of a laminated resistance member slotted alternately from opposite edges for heating the said sections and insulating material between the laminae of the resistance member and between the resistance member and the sections.

5. In a tool of the character described, the combination with a lower section, an intermediate section and an upper section, of heat insulating material between the upper and intermediate sections, a laminated resistance member slotted alternately from opposite edges lying between the intermediate and lower sections, and electrical insulating heat conducting material between the laminae of the resistance member and between the resistance member and the lower and intermediate sections.

6. In a tool of the character described, the combination with a lower section having rods extending therefrom, intermediate and upper sections and a handle having a base through which the rods extend, nuts engag-

ing the rods for securing the parts together, heat insulating material between the upper and intermediate sections, a laminated resistance member slotted alternately from opposite edges between the intermediate and lower sections, and electrical insulating heat conducting material between the laminae of the resistance member and between the resistance member and the lower and intermediate sections.

7. In a tool of the character described, the combination with lower, intermediate and upper sections, said upper section having transverse grooves for the purpose set forth, 15 and a handle, of means for securing the sec-

tions and the handle together, heat insulating material between the upper and intermediate sections, a laminated resistance member slotted alternately from opposite edges between the intermediate and lower sections 20 and electrical insulating heat conducting material between the laminae of the resistance member and between the resistance member and the lower and intermediate sections.

In testimony whereof I affix my signature, 25 in presence of two witnesses.

JOSEPH L. O'BRIEN.
